Specification for Design.

Patented Apr. 20, 1920.

Application filed September 9, 1919. Serial No. 322,760. Term of patent 7 years.

To all whom it may concern:

Be it known that I, DENHAM GRINDLEY NORMAN, a subject of the King of Great Britain and Ireland, residing at Stoke-upon-Trent, county of Stafford, England, have invented a new and original Design for a Dish, of which the following is a specification, reference being had to the accompanying drawing, forming part thereof.

Figure 1 is a top plan view of a dish, showing my new design. Fig. 2 is a side elevation of a dish showing my new design.

I claim:

The ornamental design for a dish as shown.

DENHAM GRINDLEY NORMAN.
